Des. 240,104
Patented June 1, 1976

240,104

COMBINED FILE AND DISPLAY RACK

Sven-Eric Juhlin, Gustavsberg, Sweden, assignor to AB
Gustavsbergs Fabriker, Gustavsberg, Sweden

Filed Dec. 24, 1974, Ser. No. 536,169

Claims priority, application Sweden July 11, 1974

Term of patent 14 years

Int. Cl. D6—04

U.S. Cl. D6—189

The figure is a perspective view of a combined file and display rack.

All four sides of the stand are identical as seen in elevation.

The underside of the stand is plain.

I claim:

The ornamental design for a combined file and display rack, as shown and described.
